UNITED STATES PATENT OFFICE.

GEORGE J. SCHNEIDER, OF DETROIT, MICHIGAN, ASSIGNOR TO AMERICAN ELECTRICAL HEATER COMPANY, OF DETROIT, MICHIGAN, A CORPORATION OF MICHIGAN.

ELECTRIC COOKER.

No. 825,938.

Specification of Letters Patent.

Patented July 17, 1906.

Application filed June 28, 1905. Serial No. 267,407.

To all whom it may concern:

Be it known that I, GEORGE J. SCHNEIDER, a citizen of the United States, residing at Detroit, in the county of Wayne and State of Michigan, have invented certain new and useful Improvements in Electric Cookers, of which the following is a specification, reference being had therein to the accompanying drawings.

10 The invention relates to electric cookers, and is more particularly designed for use in broilers.

The invention consists in certain novel features of construction, as will be more fully 15 hereinafter set forth.

In the drawings, Figure 1 is a cross-section through the cooker. Fig. 2 is a perspective view of one of the removable heaters detached. Fig. 3 is a perspective view of the complete 20 heater.

As shown, A and B are two end plates, preferably formed of cast metal and preferably having lugs or standards C formed integral therewith. The front frame A is provided with an opening D, which may be closed by hinged doors E, the latter being slightly cut away at the center to form an inspection-opening F.

G is a sheet-metal casing connecting the 30 frames A and B and preferably secured to inwardly-extending marginal flanges thereon.

The electric heaters are arranged within the casing C and preferably at each side thereof upon opposite sides of the opening D in the frame A. These heaters are formed of suitable high-resistance electric conductors capable of developing the required heat when an electric current is passed therethrough.

To prevent danger of direct contact between the heating-conductors and the food placed within the casing, I have devised a grate of the following construction: H is a grate or open frame extending parallel to the side of the heater between the front and rear frames A and B. This grating forms a mounting for the heating-conductor I, which is preferably in the form of coils of wire. These coils are arranged on the rear side of the grating—that is, on the side adjacent to the side of the casing—and the coils are so arranged as to expose the greater part thereof in line with the openings in the grating.

The grating itself is preferably formed of metal, and to insulate it from the heating-coils it is preferably enameled with a suitable 55 insulating material.

In the specific construction illustrated in Fig. 2 the grating H is formed of a substantially rectangular outer frame a, a longitudinally-extending central bar b, and a series of 60 vertical bars c, extending between the top and bottom bar and the central bar, these vertical bars being staggered on opposite sides of the central bar. If the insulation is sufficiently perfect, the heating-coils may be strung directly upon the grating H, and the latter may be provided with integral pins or lugs d, around which the wire at opposite ends of the coils is passed. If desired, further security in insulation may be provided by arranging 65 insulating-spoils upon these pins in addition to the enameled facing. It is desirable to have a construction in which the grating may be easily cleansed when necessary, and to this end I have mounted the grating H so 70 as to be easily removable from the casing. As shown, this is accomplished by providing lugs J and guide-flanges K upon the front and rear frames A and B. The guide-flanges K are arranged to coöperate with projecting 75 lugs L on the grating H, so that the latter may be slid upward into the casing and will be held therein properly positioned by said flanges. The grating is then secured by 80 screws engaging the lugs M on the grating to the lugs J on the front and rear frames. The 85 electric connections for the heating-conductors are automatically established upon the positioning of the grating by providing insulated contact-pieces N, mounted on the frame, 90 and coöperating contact-pieces O on the grating H. These are so arranged that when the 95 grating is in the position indicated in Fig. 1 the members N and O are in contact. From the contact-pieces N the current is conveyed through insulated conductors P, leading to suitable binding-posts Q on the outside of the casing.

With the construction described the radiation from the heating-coils I will pass through 100 the spaces between the grate-bars c and will be protected against the food which is entered through the door-opening D. At the same time the heating-conductors are effec-

tually guarded from contact with the food or with the holder therefor by the grating H.

What I claim as my invention is—

1. In an electric cooker, the combination with a heating-conductor, of a protecting-grating therefor, said conductor being arranged to expose the greater portion thereof for radiation through the spaces of the grating. 40
2. In an electric cooker, a grating having parallel spaced bars and an electric heating-conductor guarded by said grating extending back and forth opposite the spaces between said bars. 45
3. In an electric heater, the combination with a grating of a heating-conductor mounted upon one side of said grating, exposed to radiate its heat through the opening in said grating. 50
4. In an electric cooker, a grating having parallel bars and a heating-conductor mounted upon said bars arranged to extend back and forth thereon opposite the openings between said bars. 55
5. In an electric cooker, a grating provided with parallel bars and a heating-conductor comprising coils extending back and forth across said grating between said bars and mounted upon the grating. 60
6. In an electric cooker, the combination with a casing, of a grating removably secured within said casing, and a heating-conductor mounted upon said removable grating. 65
7. In an electric cooker, the combination with a casing, of a grating removably secured

within said casing, a heating-conductor mounted upon said grating and removable therewith and coöperating contacts upon said casing and grating, through which current is conveyed to the heating-conductor. 40

8. In an electric cooker, the combination with a casing, of a grating secured within and parallel to one side of said casing, and a heating-conductor arranged in the space between said grating and the side of the casing and exposed to radiate its heat through the opening in the grate. 45

9. In an electric cooker, the combination with a casing having an opening at one end thereof, of a grating within said casing parallel to the side thereof and adjacent to said opening, and a heating-conductor arranged in the space between said grating and the side of the casing and exposed to radiate its heat through the openings in the grating. 55

10. In an electric cooker, the combination with a casing having parallel side walls, an opening in one end thereof, of a pair of gratings arranged upon opposite sides of said opening within said casing, and heat-conductors arranged in the space between said gratings and the adjacent sides of the casing and exposed to radiate heat through the openings in the grating. 60

In testimony whereof I affix my signature 65
in presence of two witnesses.

GEORGE J. SCHNEIDER.
